UNITED STATES PATENT OFFICE.

ATWATER E. BROCKETT, OF EVERETT, MASSACHUSETTS, ASSIGNOR TO
CHARLES M. MARTIN, OF BOSTON, MASSACHUSETTS.

DESIGN FOR A TOY BANK.

SPECIFICATION forming part of Design No. 29,685, dated November 15, 1898.

Application filed August 6, 1898. Serial No. 687,991. Term of patent 3½ years.

To all whom it may concern:

Be it known that I, ATWATER E. BROCKETT, a citizen of the United States, residing at Everett, in the county of Middlesex and State of Massachusetts, have invented and produced a new and original Design for Toy Banks, of which the following is a full, clear, and exact specification, reference being had to the accompanying drawings, forming part thereof.

10 Figure 1 is a plan view of the toy bank, and Fig. 2 is a transverse sectional view of the same.

In general appearance my design resembles a wheel formed with a large hollow tire, but 15 without spokes, the tire being united by two flat disk-like webs. Said tire-like portion A is, as shown more clearly in Fig. 2, a tubular annulus the tubular diameter of which is quite large in comparison with the outside diameter of the bank. This tubulus A is not 20 completely united, but is open throughout

its entire inner circumference along a plane which separates the two webs 3 and 4. Said web 3 is perfectly plane and unbroken, but the other web 4 is formed with a central hole 25 through it about equal in diameter to the internal diameter of the annulus A. Said webs do not touch each other, but are separated by a space about equal to that shown in Fig. 2.

Having described my invention, what I 30 claim as new, and desire to secure by Letters Patent, is—

The design for a toy bank, herein shown and described.

In testimony that I claim the foregoing invention I have hereunto set my hand this 15th day of June, A. D. 1898.

ATWATER E. BROCKETT.

Witnesses:

CHARLES M. MARTIN,
A. B. UPHAM.
